UNITED STATES PATENT OFFICE

156,308

BAKERY CARTON

Richard Ash, Brooklyn, N. Y., assignor to Joe Lowe Corporation, New York, N. Y., a corporation of Delaware

Application November 23, 1948, Serial No. 149,789

Term of patent 14 years

(Cl. D58—12)

To all whom it may concern:

Be it known that I, Richard Ash, a citizen of the United States, residing in Brooklyn, in the county of Kings and State of New York, have invented a new, original, and ornamental Design for Bakery Carton, of which the following is a specification, reference being had to the accompanying drawing, forming a part thereof, in which:

The lining in the drawing indicates transparent windows, and the stippling is for shading only.

I claim:

The ornamental design for a bakery carton, as shown and described.

RICHARD ASH.
